UNITED STATES PATENT OFFICE.

CHARLES D. McARTHUR, OF PITTSBURGH, PENNSYLVANIA, ASSIGNOR TO BLAW STEEL CENTERING COMPANY, OF PITTSBURGH, PENNSYLVANIA, A CORPORATION OF NEW JERSEY.

TUNNEL-FORM.

1,082,700.

Specification of Letters Patent. Patented Dec. 30, 1913.

Application filed May 7, 1912. Serial No. 695,711.

To all whom it may concern:

Be it known that I, CHARLES D. McARTHUR, a citizen of the United States, residing at Pittsburgh, in the county of Allegheny and State of Pennsylvania, have invented certain new and useful Improvements in Tunnel-Forms, of which the following is a specification.

The invention relates to tunnel forms, and 10 has for its primary objects; the provision of a tunnel form having improved means for supporting the arch section employed, and for maintaining the side sections in proper relation and at the same time permit of the 15 collapsing thereof; and the provision of a form having improved means for handling the concrete or other material used in the construction of the tunnel lining. One embodiment of the invention is illustrated in 20 the accompanying drawings, wherein—

Fig. 1 is an end elevation of the right hand end of the form as shown in Fig. 3, Fig. 2 is an end elevation of the other or 25 hoist end of the framework of the form, and Fig. 3 is a longitudinal section on the line III—III of Fig. 2.

The apparatus in its preferred form includes a pair of side sections built up of 30 commercial sections forming ribs, and covered with a metal sheathing, an arch section which can be operated independently of the side sections, and a movable framework mounted upon a track and supporting the side and arch sections in such manner that 35 they may be collapsed upon the framework and moved longitudinally of the track, the said framework carrying a plurality of tracks and a hoist so arranged that a dump car may be lifted bodily and moved to any 40 desired point upon the framework.

Referring to the drawings, 1, 1, are the ribs of the side sections of the form, which 45 ribs carry a lagging 2, 2, preferably of sheet metal; and 3, 3, are sections of a truss, such truss when taken with the wood lagging 4 constituting the arch section which extends from the upper edge of one side section to the upper edge of the other side section. The lower edges of the truss sections 3, 3, 50 are secured releasably to the upper edges of the side sections, by means of the relatively short connecting members 5, 5, which members 5, 5, are connected at their upper ends to the ribs 6, 6, constituting a part of the 55 truss sections, and at their lower ends the

upper ends of the ribs 1, 1, the connections at one or both ends of such short connecting members 5 being detachable. When these members 5, 5, are detached and the strips of lagging 4 opposite thereto removed the arch 60 section can be moved downward and the side sections can be moved inward.

The arch section and the side sections are supported upon the movable framework as shown in Fig. 1, and consisting of the inclined channels 7, 7, and the transverse channels 8 and 9. As indicated in Figs. 1 and 3, the lower ends of the channels 7, 7, on each side are provided with longitudinally extending channels 10, and these channels 10 70 form a framework carrying the wheels 11, such wheels being mounted upon a track 12. The side sections are pivoted to the framework by means of the metal members 14, 14, and 15, 15 secured respectively to the ribs 75 1, 1, the members 14, 14 being provided with the laterally extending slots shown in dotted lines through which the bolts 13, 13, carried by the members 15, 15, extend. The framework and the side sections are moved toward 80 and from the frame by means of the turnbuckles 16, 16, and 17, 17, and by means of the threaded rods 18, 18, adjacent the lower edges of the side sections. These rods 18, 18 85 carry nuts 19, 19 swiveled to the framework and adapted to receive a turning bar. By means of these bars 18 and the turnbuckles 16 and 17 the side sections are moved in and out and held rigidly in any desired position.

The truss sections 3, 3 are supported upon 90 lifting jacks 20, 20 carried by the members 15, 15, and the truss sections are guided in their vertical movement, by means of pins or bolts 21, 21, which slidingly engage slots 22, 22 in the plates 23, 23, which are rigidly 95 secured to the framework. It will be seen that when the connections 5, 5 are detached the arch section is free to move vertically independently of the side sections, and is guided in such movement by the pins 21, 21, 100 and that the side sections are free to swing inwardly independently of the arch section.

In order to supply the concrete or other material for the lining of the tunnel, the tracks 24, 25, 26, and 27 for dump cars are 105 provided upon the transverse channels 9 and 8 of the framework, such tracks extending longitudinally of the framework through the distance marked A in Fig. 3 of the drawing, the distance B on this figure constituting 110

tuting the hoist portion of the framework and carrying a transfer car to be later described. Material brought on the dump cars along the tracks 24, 25, 26, and 27 is discharged to a position behind the lagging in any desired manner, one means being by the employment of chutes 28 shown in dotted lines on Fig. 1, which chutes can be moved from place to place and discharge at their lower ends through openings in the lagging formed by swinging back hinged portion 29 thereof, as indicated in dotted lines. However, various means may be employed for getting the material for the lining from the cars to its position back of the lagging, and such means does not constitute an essential part of my invention.

The portion marked B of the framework as shown in Fig. 3 constitutes the hoist portion of the framework, and the tracks 24, 25, 26, and 27 do not extend across this portion of the framework, however, two other tracks 30 and 31 which extend transversely of the framework and carry the transfer cars 32 and 33. These transfer cars 32 and 33 in turn carry the tracks 34 and 35, which tracks 34 and 35 are adapted to align with the tracks 24 and 25, and 26 and 27, when the transfer cars are moved laterally to their proper positions. The function and utility of this apparatus will be apparent from a consideration of the method of handling the dump car containing the material. This dump car 36, comprises in the form illustrated a bucket 37 pivoted at 38 upon the framework of the car and having a bail 39. This car is mounted upon a track 40 which extends longitudinally of the framework substantially at the center thereof. This car is brought to the position as indicated in Figs. 2 and 3 and lifted bodily by means of the cable 41 passing over the pulleys 42 and 43 (Fig. 3), the transfer cars 32 and 33 being in position to one side of the center line of the framework, as indicated in Fig. 2, in order to permit of the elevation of the cars past such transfer cars. If it is desired to use the car upon the lower tracks 26 or 27, the car is hoisted to a position just above the channels 8, after which the car 33 is moved laterally to a position beneath the dump car, and the dump car is lowered until its wheels rest upon the tracks 35. The transfer car 33 can then be moved laterally until its tracks 35 align either with the tracks 26 or 27, at which time the dump car can be shoved from the track 35 to the tracks 26 or 27, and moved longitudinally until it reaches the desired point of discharge. It will be understood that the portion marked A of the form as shown on Fig. 3 is in practice relatively much longer than the portion marked B, and that when it is desired to concrete back of the lagging op-

posite the portion marked B the dump car remains upon the tracks 34 and 35, the transfer car being moved laterally upon the tracks 30 and 31 until the dump car is in position to discharge behind the lagging. It will be understood that any form of dump car may be used, and this term is used in its broad sense to indicate any car from which a discharge may occur.

In operating the apparatus the framework carrying the side and arch sections is brought to the position of use along the track 12, the side and arch sections being at such time in their innermost positions. At this time the connecting members 5, 5 are detached and the jacks 20, 20 are in lowered position. When the framework reaches a position for use the turnbuckles 16 and 17 and the rods 18 are operated to expand the side sections to their proper positions, and the lifting jacks 20 are operated to raise the truss sections 3, 3 to their position of use, after which the connecting members 5, 5 are secured to the ribs of the side and truss sections, and the operation of supplying the concrete behind the lagging 2 is begun. During the first part of the filling in operation the tracks 26 and 27 are utilized, the concrete being brought to position beneath the hoist, along the track 40, after which it is raised to position above the transfer car 33. After the transfer car has been moved in position beneath the dump car, such dump car is lowered until its wheels engage the track 35. The transfer car is then moved laterally to the edge of the framework, at which time a discharge may occur to a point behind the lagging, or the track 35 is brought into alignment with one of the tracks 26 or 27, and the dump car moved onto one of such tracks and carried to the position at which it is desired to discharge behind the lagging. At a later stage in the operations the dump car is carried to the tracks 24 and 25, the operation being substantially the same as heretofore described with respect to the lower tracks.

Having thus described my invention and illustrated its use, what I claim as new and desire to secure by Letters Patent, is the following:

1. In combination in a tunnel form, a track, a framework mounted on the track, a side section at each side of the framework comprising upright ribs and lagging thereon, means whereby the side sections are moved toward and from the framework, a rigid arch section comprising ribs and lagging mounted on the framework for vertical movement independent of the side sections and with the ends of its ribs spaced away from the ends of the ribs of the side sections, and releasable joining members between the ends of the ribs of the arch and side section.

2. In combination in a tunnel form, a track, a framework mounted on the track, a side section at each side of the framework comprising upright ribs and lagging thereon, means whereby the side sections are moved toward and from the framework, a rigid arch section lying above the side sections, lifting means carried by the framework and engaging the arch section, and slip connections between the framework and arch section permitting a vertical movement of the arch section but preventing a lateral movement.
3. In combination in a tunnel form, a track, a framework mounted on the track, a side section at each side of the framework comprising upright ribs and lagging thereon, means whereby the side sections are moved toward and from the framework, a rigid arch section comprising ribs and lagging mounted on the framework for vertical movement independent of the side sections and with the ends of its ribs spaced away from the ends of the ribs of the side sections, releasable joining members between the ends of the ribs of the arch and side sections, means for moving the arch section vertically, and slip connections between the framework and arch section permitting a vertical movement of the arch section but preventing lateral movement.
4. In combination in a tunnel form, a track, a framework mounted on the track, side and arch sections carried by the framework, a car track beneath the framework extending longitudinally thereof, a dump car therefor, a car track on the framework parallel to such last car track but to one side thereof, a transfer car mounted on the framework for movement transversely of the said last car track and having a car track for receiving the dump car from the car
- track beneath the framework and arranged to align with the car track on the framework, and a hoisting means on the framework for lifting such dump car and depositing it upon the car track on the transfer car.
5. In combination in a tunnel form, a track, a framework mounted on the track, side and arch sections carried by the framework, a car track beneath the framework extending longitudinally thereof, a dump car therefor, a transfer car mounted on the framework for movement transversely thereof and having a track extending parallel with the said car track, and a hoisting means upon the framework for lifting the dump car from the car track beneath the framework and depositing it upon the track on the transfer car.
6. In combination in a tunnel form, a track, a framework mounted on the track, side and arch sections carried by the framework, a car track beneath the framework extending longitudinally thereof, a dump car therefor, a transfer car mounted on the framework for movement transversely thereof and having a track extending parallel with the said car track, a plurality of car tracks extending longitudinally of the framework for a portion of its length with which the track on the transfer car is adapted to align, and a hoisting means on the framework for lifting the dump car from the car track beneath the framework and depositing it upon the track on the transfer car.
- In testimony whereof I have hereunto signed my name in the presence of the two subscribed witnesses.

C. D. McARTHUR.
